UNITED STATES PATENT OFFICE

2,583,525

METHOD FOR SEALING AND TERMINATING
TUBULAR DEVICESJoe Yoder, Erieside, Ohio, assignor to General
Electric Company, a corporation of New YorkOriginal application April 17, 1943, Serial No.
483,470. Divided and this application August
15, 1946, Serial No. 690,661

2 Claims. (Cl. 49—78)

1

This invention relates to methods for basing envelope constructions for electrical devices, including electric lamps and discharge devices.

This application is a division of my copending patent application Serial No. 483,470 filed April 17, 1943, which issued as Patent 2,535,773, December 26, 1950 and which is assigned to the assignee of this application.

My invention relates to new and improved methods of sealing and terminating tubular devices such as tubular vitreous envelopes for electric discharge lamps.

The invention is especially advantageous for electric lamps whose envelopes have tubular necks or end portions, including lamps of tube form such as ordinary fluorescent lamps of the usual positive column discharge type—although it is also adaptable to other types of lamps and electric translation devices. In suitable forms of embodiment, the invention affords advantages in maximum utilization of the tubular envelope wall for useful light output; simplicity and economy of envelope fabrication; ease and cheapness in the basing operation; simplicity and ruggedness of the base, and ease and cheapness in its manufacture; and economy of material in the construction of the base. Indeed, the invention even permits of dispensing entirely with a base as a separate structure, by incorporating the usual base contact terminals into the envelope construction.

In forms of embodiment of the invention here illustrated and described, a tubular discharge envelope is constructed with a re-entrant-walled end, embodying an end-piece or wall set back behind the extremity of the tubular wall. In some forms, this set back end portion is shown as a stem flare and inlead seal of the general type now commonly used in fluorescent lamps; while in other forms, it is shown as an inlead seal disc which is in itself rather like those of certain vacuum-tubes. The set-back end portion is connected to the extremity of the main tubular wall by a reentrant annular or frusto-conical inner wall, which coacts with the end piece to form an external end cavity. The preferred method of fabrication of the reentrant end wall that is hereinafter described is to fuse the tubular wall to the edge of the end-piece and to shift the end-piece further inward into the tube, while the material is soft, thus drawing, stretching, and retroverting the joint and the tubular wall "outside-in" into the tube to form this reentrant inner wall. A contact-terminal-carrying insulative base may be cemented over and into the

2

external end cavity, or may even consist essentially of an insulative thermoplastic filler adherent to the internal cavity wall and to contact-terminal parts or "biposts" embedded and anchored directly in the plastic, substantially without direct attachment to the envelope, though connected to the inlead wires. Alternatively, the contact-terminals may be sealed into or through the reentrant end wall of the envelope, and thus anchored or attached directly and more firmly to the latter. When the contact-terminals are thus anchored strongly enough in a sufficiently rugged end wall, the insulative filler in the end cavity may be omitted, doing away entirely with any distinct base structure.

Various other features and advantages of the invention will become apparent from the description of species and forms of embodiment and from the drawings.

In the drawings, Figs. 1, 2, 3 and 4 are fragmentary longitudinal sectional views illustrating stages in the fabrication of envelope ends according to the invention.

Figs. 5 and 6 are views similar to Figs. 1 and 4 illustrating another form of construction and its manufacture, and Figs. 7 and 8 are views similar to Figs. 5 and 6 illustrating a baseless construction.

As illustrated in Fig. 3, the lamp L may be a discharge lamp of tubular form and of positive column low-pressure type, comprising a glass envelope tube 10 with a reentrant-walled end 11. The reentrant end 11 is shown as forming part of a cathode mount that includes a short hollow glass stem tube or flare 12 terminating in a fused seal 13 through which the current leads 14, 14 to the cathode 15 enter the envelope 10. The cathode 15 may consist of the usual coiled coil of tungsten wire coated with activating oxides, such as a mixture including barium and strontium oxides, and may be supplemented with the usual unactivated anode(s) 16 formed by transverse extensions of lead wire(s) 14. When the device L is a fluorescent lamp, its tubular wall 10 is made luminescent under excitation by the radiation due to the electrical discharge therein, as by means of an internal coating of phosphor 17 on said wall. The envelope 10 may contain a low pressure atmosphere of starting gas, such as argon at a pressure of 2 to 4 mm. of mercury, and also a vaporizable and ionizable working substance, here indicated by a drop of mercury 18, which may exceed the amount that will vaporize during operation of the lamp L. The envelope end may also be provided with an

exhaust tube 24 opening through the stem seal 13 but itself sealed-off at its outer end 25.

The envelope end portion 10 is provided with a suitable base structure (not shown) of a type which leaves the luminescent envelope wall 10 exposed and unobscured right to the very extremity of the envelope tube and which is provided with suitable contact terminals which may project outwardly from the base substantially beyond the extremity of the main tube (as shown in Fig. 8) and to which the current lead wires 14, 14 are electrically connected as by soldering or welding.

It will be appreciated that as the base leaves the luminescent envelope wall 10 exposed and unobscured right to the very extremity of the envelope tube, this wall can be fully utilized for useful light output; and when the envelope is rendered luminescent by a phosphor coating or layer at its inside, this layer may usefully extend to the very end of the wall 10, and even inward back on the wall of the reentrant cavity 11. It will be understood that for the usual fluorescent lamp the other end of the lamp is provided with a similar electrode and base structure.

In fabricating an envelope end for a fluorescent lamp according to this invention, the first step of the operation may correspond in a broad way to present fluorescent lamp practice. As shown in Fig. 1, a cathode mount M such as usually used for fluorescent lamps—comprising as end piece for the envelope a so-called "flare" 12 through whose seal 13 the current leads 14, 14 extend to the cathode 15—is about to be sealed into the lower end of an upright envelope tube 10 by means of gas flames from circumjacent burners 32. Usually, envelope tubes for fluorescent lamps are made with their ends reduced in diameter by an inward offset of the edge, and the tube end 10 is so shown with a reduced diameter neck end portion 33 in Fig. 1. Also, the envelope tube 10 is commonly and preferably coated internally with phosphor powder 17 before the mount M is sealed into it; but to prevent phosphor on the tube edge or neck end portion 33 from interfering with the sealing in, this portion 33 is left uncoated, or the coating on it is removed in advance of the sealing in operation. The tube 10 may be held in a vertically shiftable clamp 34, and the mount M may be held or supported in proper sealing-in relation to the tube 10, at a predetermined sealing line thereof, by a vertically shiftable hollow metal support 35 which receives the exhaust tube 24 and has a more or less conical head 36 that fits up into the stem tube 12. The support 35 may be slotted and grooved as shown to accommodate the lead wires 14, 14. In accordance with usual sealing-in practice, the burners 32 may revolve relative to the parts 10, M, 34, 35, or vice versa. The flames from the burners 32 play on the edge portions 33 and 11', respectively of the tube 10 and of the flare 12 to heat and soften them until they coalesce in a "fused" seal. However, it will be understood that other means of heating the glass might be employed in forming the seal.

If performed as just described without anything further, the sealing-in operation would result after cooling in a tube end conformation such as illustrated in Fig. 2, where the edge 11' of the flare 12 joins the reduced tube edge or neck end portion 33 almost at a sharp angle, and the reduction in diameter at 33 is retained almost unmodified. In former practice, this was the case; and the reduction at 33 afforded room

and even a practicable lip-hold 37 for basing cement to secure to the envelope end 10 a cap-shaped or skirted base of the conventional type in common use at present on tubular fluorescent lamps.

In accordance with this invention, the end conformation 33 that is shown in Fig. 2 is modified. In part, at least, this may be effected by a measure that also assists in uniting the hot edges of the parts 11, 33: namely, by direct positive pressure on these softened and more or less coalescent edges, by means of a metal molding head 38 on a sleeve 39 shown in Fig. 1 as telescoped around the support 35. This head 38 is moved up against the soft parts to finally seal them together (if this is required), and to round and true up the corner formed by their union. The effect of this is to more or less obliterate the shoulder or lip 37, shown in Fig. 2, besides regularizing the tube end conformation and shifting the whole mount M further inward in the axial direction into the tube 10.

The inward displacement of the stem tube or flare 11, 12 by action of the head 38 on the seal at 33 may be supplemented or substituted by an axial inward shift otherwise effected. If resorted to as a measure additional to the pressure of the head 38 on the seal at 33, this may be done either during such pressure or afterward. In either case, the flare 12 (and the whole mount M) is shifted inward into the tube end portion 10, while the material is heated and soft, by force exerted more directly on the mount or flare, thus drawing and retroverting the edge or marginal portion of the envelope wall at 33 reentrantly outside-in and stretching or pulling it straight (more or less perfectly) into an inturned frusto-conical annulus 33b at the base of the flare 12—almost corresponding in conicity to the flare itself—all as shown in Fig. 3, where the slight angle or difference of conicity of the reentrant wall at 31 corresponds to the fused seal between the original flare 12 and the inturned tube edge portion 33b. This is preferably done while the portions of tube 10 and flare 12 are still soft from the heat used in sealing them together as above described in connection with Fig. 1, rather than by reheating them. In this operation, the original offset at 33 in Fig. 1 is faired away and virtually or nearly abolished. If the material of the tube edge portion and of the flare is suitably soft over sufficiently wide zones, and the mount M is shifted inward far enough, the angle at 31 may be flattened out until all trace of it virtually disappears, resulting in a reentrant end wall of substantially uniform conicity, as shown in Fig. 4. Indeed, part of the cylindrical tube wall shown in Figs. 1 and 2 will generally be turned outside-in and thus incorporated into the reentrant end wall. The axial inward shift of the mount M and flare 12 may be produced by pushing upward on them by means of the support 35 while the envelope 10 is held fixed by means of the clamp 34, or by pushing downward on the envelope 10 by means of the clamp 34, or by a combination of such movements—or in any other suitable way.

It will be seen that the turning outside-in of the tube wall at 33 (and above) as has been described not only improves the conformation of the tube end and gets rid of the unsightly reduction in diameter at 33 without necessity for a skirted base to hide it, but also results in having the luminescent cylindrical tube wall 10 extend right to the very end of the tube, with the

resultant advantage already mentioned in connection with Fig. 3. Even if the envelope tube end 10 lacked the end reduction 33 or any corresponding feature, the retroversion outside-in of part of the cylindrical tube wall would produce a similar advantage in respect of the zone of fusion produced in sealing the flare 12 to the tube-end edge.

Figs. 5 and 6 illustrate the application of the invention to a mount Mc in which the flare type end piece of Figs. 1-4 is replaced by a simple glass disc end piece 11c which the lead-wires 14, 14 penetrate through bead-like internal and external seal protuberances 40, 40, and through which the axial exhaust tube 24 opens centrally between the seals 40, 40. Such a mount may be fabricated by the glass-working methods commonly used in fabricating the multi-lead ends of vacuum tubes of various kinds, with the slight modification naturally indicated by the fact that only two leads 14, 14 are sealed through the disc 11c. The mount Mc is shown in Fig. 5 as supported by a vertically movable hollow metal support 35c that receives the exhaust tube 24 and has an enlarged flat head 36c with flared apertures for the leadwires 14, 14 and the seals 40, 40. Instead of having reduced ends as at 33 in Fig. 1, the envelope tube 10c may originally be of uniform bore; and instead of the method usually employed for sealing in fluorescent lamp mounts M as illustrated in Fig. 1, the mount Mc may be sealed in accordance with usual incandescent lamp practice: that is to say, the upright tube portion 10 is placed around the mount disc 11c with the latter some distance (e. g., some 1 to 1½ inches) above the open lower tube end in sealing-in relation thereto at a predetermined sealing line thereof, and the tube 10c is then heated at the region of the sealing line by flames from the circumjacent burners 32 until it draws and "necks in" into a fused seal with the disc edge by the weight of the subjacent tube end, which ultimately fuses through below the seal and drops off. Thereupon the support 35c may be raised higher to shift the disc 11c and the whole mount Mc further inward into the tube 10, thus pulling, stretching, and turning or retroverting the fused seal (and even the soft wall of the tube 10) outside-in into the end of the tube 10 as shown at 33c in Fig. 6. The reentrant-ended tube may then be based in the manner previously described, or in any other suitable manner.

Figs. 7 and 8 illustrate a variant of the method and construction shown in Figs. 5 and 6 whose distinctive feature is that instead of having "through" leadwires 14, 14 sealed through the disc end piece 11d and afterward connected to contact terminal pins of a distinct or separate base structure, the contact terminal pins 21d, 21d are themselves sealed directly through the disc 11d and 40d, 40d and carry short internal leadwires 14d, 14d between which the cathode coil 15 is connected. In other respects, this construction and its fabrication may correspond to what has already been described in connection with Figs. 5 and 6, including the pulling, stretching, and turning in of the fused seal at 33d and the wall of the tube 10. Thus the lamp "base" is essentially merged in the lamp envelope end construction, and special basing operations are dispensed with. The pins 14d, 14d are firmly

fixed in the glass of the end construction, which is very strong and rigid. The cavity of the reentrant lamp end may if desired be filled in around the pins 14d, 14d and the exhaust tube seal 25d with an insulative filler of cement, sealing-wax, or other thermoplastic, like Bakelite, for instance, thus fortifying the anchorage of the pins, and protecting the seal 25d and the reentrant tube end 11d from accidental damage.

It will readily be appreciated that the constructions illustrated in Figs. 6 and 8 not only allow of rendering the tube wall luminous with phosphor 17 right up to the very end 11d and even on the main central area of the latter, but also allow of placing the cathode 15 as close as possible to the very end of the tube wall, so that all the phosphor coating shall be effectively excited by the electric discharge in the tube.

In Figs. 2, 3, and 4 to 8, various parts and features are marked with the same reference characters as are applied to corresponding parts in the earlier figures, in order to dispense with repetitive description, a distinctive letter being added where such distinction appears needful.

What I claim as new and desire to secure by Letters Patent of the United States is:

1. The method of manufacturing a tubular fluorescent lamp having its envelope coated internally with fluorescent material to the very ends thereof, which method comprises positioning an end piece in sealing-in relation adjacent an end of an envelope coated internally with fluorescent material except for a limited uncoated end portion of its wall extending inwardly beyond the region of the envelope wall to be sealed to the end piece, thermally softening and sealing the said uncoated end portion of the envelope to the edge portion of the end piece, and, while the material is soft, turning the entire uncoated end portion of the envelope, inwardly of the seal, reentrantly outside-in by shifting the end piece inward into the envelope.

2. A method of manufacturing a tubular fluorescent lamp having its envelope coated internally with fluorescent material to the very ends thereof, which method comprises positioning an end piece in sealing-in relation to one end of an envelope having reduced diameter neck end portions and coated internally with fluorescent material except for the said neck ends thereof which are uncoated, thermally softening and sealing the uncoated neck end portion of the envelope to the edge portion of the end piece, and, while the material is soft, turning the entire uncoated neck end portion of the envelope wall reentrantly outside-in by shifting the end piece inwardly of the envelope.

JOE YODER.
